MOSLER SAFE COMPANY, OF HAMILTON, OHIO, A CORPORATION OF NEW YORK

COMMUNICATING AND VENTILATING DEVICE FOR VAULTS

Application filed July 6, 1929. Serial No. 376,364.

This invention relates to means for ventilating compartments, such as bank vaults, which are substantially air-tight when they are closed, and for instituting vocal communication between the interior and the exterior of a closed vault. The device is particularly designed to overcome the danger of suffocation which threatens persons locked within a vault by robbers, or by accident, and likewise has for a purpose the provision of a means for persons enclosed in the vault to communicate with those on the outside.

An object of the invention is to provide means for establishing passages through a wall of a closed vault, said means being operable from the interior of the vault.

Another object is to provide means for introducing fresh air into a closed vault and for ridding the compartment of foul air.

A further object is the provision of means of the class described which are not discernible from the exterior of the vault.

These objects are attained by the means described herein and set forth in the accompanying drawings, in which:

Fig. 1 is a front elevational view of the operating panel of this invention positioned upon an interior wall of a vault, parts of the wall being broken away.

Fig. 2 is a view taken on line 2—2 of Fig. 1, and showing the communicating and ventilating device in the closed position.

Fig. 3 is a view similar to Fig. 2, showing the device in its open or operative position, parts being broken away.

Fig. 4 is a view taken on line 4—4 of Fig. 2.

Fig. 5 is a view taken on line 5—5 of Fig. 2.

Figs. 6 and 7 are perspective views showing details of the device.

With reference to the drawings, the vault wall 10 is shown as provided with the usual outer wall plate 11 and an inner wall plate 12. Between these plates and positioned within the wall 10 is a narrow, tapered casing 13, which is preferably constructed of metal. Casing 13 has the top 14, the bottom 15, sides 16 and 17, and back 18, and is rectangular at any of its vertical cross sections. The open front end 19 of casing 13 extends

through the plate 11 and is flush with the outer face thereof. A central diaphragm 20 is mounted horizontally, such as by screws 21, between the sides 16 and 17 of the casing, in the forward portion thereof, its front end being flush with the forward end of casing 13. A plug 22, which may be of copper or the like, is positioned within casing 13 and conforms to the inner contour of the forward portion of the casing, the plug being shorter in length than the casing. The rear portion 23 is of harder material than the body portion of plug 22 and is secured thereto by means of screws 24. A horizontal, transverse slot 25 bisects the front portion of plug 22, being of somewhat greater length than diaphragm 20. Slot 25 receives diaphragm 20 which serves as a supporting guide upon which plug 22 is slidably movable. Small drill proof plugs 26, in interspaced relation, are inserted through the extreme forward portions of plug 22, transversely thereof.

A section of the rear plate 12, immediately behind the positioned casing 13, is taken out in order to provide the space 27 over which the panel 28 is positioned and secured to plate 12. An electric bulb 29 on the upper portion of panel 28, directs its light downwardly upon the panel. A pair of tubes 30 and 31, having exteriorly-threaded ends, extend through panel 28 and blocks 32, into threaded holes 33 in back 18 of casing 13. Tubes 30 and 31 enter back 18 adjacent the top and the bottom thereof, respectively. Holes 34 in back 18 and in alignment with the holes 33, complete the communication of tubes 30 and 31 with the interior of casing 13. A sleeve 35 extends through panel 28 and is secured within a threaded hole 36 in back 18, somewhat above the mid-point thereof. A threaded shaft 37, within casing 13, has an enlarged end portion 38 which extends through back 18 and is revolvably mounted within sleeve 35. A shoulder 39 on the shaft 37 end 38 abuts the inner end of sleeve 35 and permits of only partial projection of end 38 through sleeve 35.

The opposite end of shaft 37 enters a threaded hole 40 in the rear portion 23 of

plug 22. A socket 41 in plug 22 is aligned with hole 40 and receives the threaded shaft 37 when the latter is screwed inwardly of the plug 22. A stud 42 is revolvably mounted in the exposed or outer end of sleeve 35 and interlocks, as indicated at 43, with the shaft end 38. A plate 44, integral with stud 43, abuts the outer end of sleeve 35, and has attached thereto the arm 45. A pin 46 extends longitudinally through stud 42 and is secured within shaft end 38, thus precluding separation of these parts. A handle 47 on the end of arm 45 provides a means for turning the stud and the shaft 37, secured thereto. An open end casing 48, enclosing the outer end of tube 31, is secured upon panel 28, and has a wire screen or guard 49 fastened over its protruding end. An electric motor 50 is secured within the casing 48 by means of three suspension screws 51, spaced apart about 120 degrees. A fan 52, driven by motor 50, is positioned in casing 48 adjacent the outer end thereof. An electric switch 53, controlling the motor 50, is positioned on the panel 28 below casing 48.

A rosette 54 provided with a threaded stud 55 is secured thereby to the outer end of diaphragm 20. The under face of rosette 54 has countersunk portions 56 divided by a central partition 57 which, when the stud 55 has been screwed into diaphragm 20 to its fullest extent, falls into substantial alignment with the end of diaphragm 20. The outer edges of rosette 54 extend above and below the exposed ends of top 14 and bottom 15 of casing 13, thus hiding from view the casing and the diaphragm and plug enclosed therein.

The use and operation of the device is as follows: By turning the arm 45 in a clockwise direction to its greatest extent, the plug 22 is moved forwardly in its casing, to the closed position of the device, illustrated in Fig. 1. When it is desired to ventilate the vault and provide communicating passageways, arm 45 is turned in the counter clockwise direction whereby the threaded shaft 37 draws plug 22 backwardly in casing 13 until the rear portion 23 of the plug abuts the inner face of the back 18 of the casing, as illustrated in Fig. 2. It should be noted that the rear portion of plug 22 in this position extends to, but not beyond the edges of holes 34 in back 18, so that no obstruction of holes 34 results. Two clear passages from the interior to the exterior of the vault have now been established, one through tube 30, upper hole 34, the channel or chamber between top 14, plug 22 and diaphragm 20, and the upper countersunk portion 56 of the rosette, and the other passage similarly formed by tube 31 and the parts opposite to those just enumerated. The switch 53 is now turned to the "on" position, and fan 52 set into motion whereby a current of fresh

air is drawn in through the lower passage. The foul air in the vault is allowed to escape through the upper passage, which also serves as a means for effecting vocal communication between the interior and exterior of the vault. 70

The device is simple in operation, in no way weakens the vault, is almost impossible to discover from the exterior of the vault, and, if so discovered, is capable of withstanding any attempts at breaking or drilling it. 75

What is claimed is:

1. A ventilating and communicating device for vaults and the like and comprising a casing with an open end, said casing being positioned in a wall of the vault with its open end extending through and flush with the outer face of the wall, a slotted plug within the casing of a size less than that of the casing, a diaphragm secured in the casing adjacent the open end thereof said diaphragm being receivable in the slot of the slotted plug, tubes opening upon the interior wall of the vault and communicating with the interior of the casing adjacent the upper and lower portions thereof respectively, and means cooperating with the plug and operable from the interior of the vault for slidably reciprocating the plug upon the diaphragm away from the front of the casing 95 to establish separate passages connecting the interior with the exterior of the vault, one of said passages being adapted to have a positive current of air moved therethrough. 90

2. A communicating and ventilating device for vaults and comprising a casing positioned in a wall of the vault and communicating with the interior and the exterior of the vault, and means within and non-removable from the casing and reciprocable from the interior of the vault for establishing and closing communication between the interior of the casing and the exterior of the vault. 100

3. A communicating and ventilating device for vaults and comprising a casing positioned in a wall of the vault and communicating with the interior and the exterior of the vault, a plug non-removably positioned within the casing and adapted to close communication between the interior of the casing and the exterior of the vault and means cooperating with the plug and operable from the interior of the vault for reciprocating said plug whereby to selectively close and establish communication between the interior and the exterior of the vault. 110

4. In a vault structure the combination with a structural vault wall having a chamber therein opening to the outside, a plug member operable from the interior side of the wall to move said plug to open and close said chamber, a pair of members providing passages between the interior of the chamber and the interior side of the wall, and means concealing the outside opening of the chamber. 125

ber and providing for outside air communication through the passages to the interior side of the wall when the plug is retracted.

5. The combination with a vault wall structure, of a casing positioned in the wall and having one end open and extending exteriorly of the vault, tube members communicating with the interiors of the vault and the casing, a plug non-removably positioned in the casing and adapted to close the open end of the casing, and means operable from the interior of the vault for reciprocating the plug within the casing whereby to selectively establish air passages from the interior to the exterior of the vault.

10 6. A communicating and ventilating device for vaults and comprising a tapered casing having its smaller end open, the casing being adapted for positioning in a wall of a vault with its open end in communication with the exterior of the vault, a diaphragm horizontally secured in the portion of the casing adjacent the open end thereof, a tapered slotted plug in the casing, said diaphragm being receivable in the slot of the plug, means cooperating with the plug and operable from the interior of the vault for reciprocating the plug upon the diaphragm whereby the plug may be selectively moved forward to close the open end of the casing and retracted to contact the closed end thereof, a pair of tube members opening to the interior of the casing above and below the plug in its retracted position such that separate 25 passageways between the interior and the exterior of the vault may be established, through one of which passageways a positive current of air may be moved, and means on the exterior of the vault for concealing the exposed portions of the device.

15 7. The combination with a vault wall structure, of a casing positioned in the wall, and means cooperating with the casing and comprising a plug non-removably positioned in the casing and reciprocable from the interior of the vault for establishing and closing separate passageways between the interior and the exterior of the vault.

20 8. The combination with a vault, of a casing positioned in a wall of the vault and having one of its ends opening upon the exterior of the vault, tube members communicating with the interior of the vault and the interior of the casing, means within and non-removable from the casing and operable from the interior of the vault for selectively closing the open end of the casing and for opening the same whereby to establish in the casing separate channels each communicating with one of said tube members, and means on the exterior of the vault for concealing the device and providing separate continuations of the channels established within the casing.

25 9. A ventilating and communicating device for vaults comprising members provid-

ing communicating passageways between the interior and exterior of the vault, one of said passageways being adapted to have a positive current of air pass therethrough, and means non-removably and reciprocably associated with said communicating members and adapted to be selectively interposed in said passageways for opening and closing communication between the interior and exterior of the vault, said means being operable wholly from within the vault.

30 10. The combination with a vault provided with ventilating passages in its walls, of a device for concealing the exterior openings of such passageways, said device comprising a plate member having on one of its faces separated countersunk portions extending inwardly of said face from the edge thereof, said plate being adapted to be fastened to an exterior wall of a vault adjacent one or more of said passageway openings and with one of said countersunk portions in registry with and covering each of such openings.

35 11. The combination with a vault, of a ventilating and communicating device comprising a casing positioned within a wall of the vault and opening upon the exterior face only of said wall, a pair of tubes communicating with the interior of the casing and the interior of the vault, and means in the casing and adjustable from the interior of the vault, said means being adapted in one position to close communication between the interior of the casing and the exterior of the vault, and in another position, to establish separate passage ways from the interior to the exterior of the vault, one of said passageways being adapted to have a positive current of air passed therethrough.

40 In testimony whereof, we have hereunto subscribed our names this 25th day of June, 1929.
